UNITED STATES PATENT OFFICE.

RUSSELL B. KINGMAN, OF ORANGE, NEW JERSEY.

SWAB.

Application filed November 3, 1925. Serial No. 66,489.

This invention relates, generally, to an instrument in the form of a swab for cleaning tubular or cylindrical structures of various kinds, such e. g. as milk Pasteurizing tubes and the like.

This invention has for its principal object to provide a novel construction of swab, either of the dry type, or of the fountain type having means for delivering water, steam or other fluid in connection with and in aid of the cleansing operations adapted to be performed by the swab.

With the general object of this invention in view, the same comprises a novel construction of swab head provided with novel scouring elements made of all-metallic fabric, or composite vegetable fiber and metallic fabric adapted to furnish an efficient abrasive material calculated to produce a thorough scouring effect upon the surfaces to which it is applied.

This invention has for a further object to provide a novel construction and arrangement of dismountable flexible and reversible swab elements, together with a novel means for operatively coupling said flexible and reversible swab elements with the head of the device.

Other objects of this invention, not at this time more particularly enumerated, will be clearly understood from the following detailed description of the same.

With the various objects of this invention in view, the same consists, primarily, in the novel construction of swab hereinafter set forth; and, the invention consists, furthermore, in the novel arrangements and combinations of the various devices and parts, as well as in the details of the construction of the same, all of which will be hereinafter more fully described, and then finally embodied in the appended claims.

The invention is clearly illustrated in the accompanying drawings, in which:

Figure 1 is a side elevation of the novel construction of swab made according to this invention, and showing the arrangement of the same when passed through a tube or the like in one direction; and Figure 2 is a similar view showing the arrangement of the swab when passed through a tube or the like in the opposite direction, to illustrate the reversing functions of the flexible swab elements.

Figure 3 is a side elevation of one form of the swab head and detachable keeper member for coupling the flexible swab elements therewith.

Figure 4 is an enlarged side elevation of the swab head illustrating a covered form thereof, and also showing the detachable keeper member ready to be applied thereto.

Figure 5 is a vertical longitudinal section of a covered form of swab head with the flexible swab elements operatively coupled therewith; and Figure 6 is a fragmentary cross section, taken on line 6-6 in Figure 5.

Figure 7 is a side elevation of a fountain type of swab head, a portion of the covering material being broken away; Figure 8 is a vertical longitudinal section through the same; and Figure 9 is a vertical sectional view of a modified form of detachable keeper member which may be employed with said fountain type of swab head, if desired.

Figure 10 is a diagrammatic plan view to illustrate one method of assembling a plurality of flexible swab elements; and Figure 11 is a diagrammatic perspective view of two flexible swab elements, as disposed for superimposition one on the other.

Similar characters of reference are employed in all of the hereinabove described views, to indicate corresponding parts.

Referring now to said drawings, the reference character 12 indicates a swab head in the form of a rigid elongated body, preferably of cylindrical conformation. Suitably attached to the lower end of said swab head is a handle member 13 of desired length suitable to the particular conditions of use to which the swab is to be put. The outer or free end of said swab body 12 is provided with an axially aligned internally screw threaded bore 14.

The reference character 15 indicates a keeper member which preferably comprises a relatively short rigid cylindrical body, preferably substantially corresponding in diameter to the diameter of said swab body 12; said keeper member is provided at its inner end with a screw threaded shank 16 adapted to screw into the bore 14 of said swab body 12. In the simplest form of my novel swab device, the swab body 12 and keeper member 15 may be uncovered as to their exterior surfaces, as indicated by the full lines in Figure 3; on the other hand,

for certain classes of work it may be desirable to cover the exterior surfaces of either or both the swab head 12 and keeper member 15 with a covering of abrasive material, indicated by the dotted-lines in said Figure 3, the character and arrangement of which will be hereinafter more particularly set forth.

The reference character 17 indicates a plurality of flexible swab elements. These swab elements are made of a metallic abrasive fabric, which is either knitted or woven from a flat metallic wire, preferably of a non-corrosive metal such as copper, to provide a relatively coarse fabric of highly efficient abrasive character. The fabric material may consist of an all metal type, or it may consist of a composite type suitably combining vegetable fibre strands with metallic strands. For example, jute threads gimped with flat copper wire, may be interwoven or knitted to provide the fabric; or such metal gimped jute threads may be suitably interwoven with either or both metallic cross threads and vegetable fiber cross threads. The flexible fabric is preferably provided with metallic material which is calculated to produce the desired abrasive effects adapted to provide adequate scouring efficiency. Where strong abrasive effect is the desideratum, an all metallic fabric may be used; but if a certain amount of absorbent effect is desired, the combined metallic and vegetable fiber fabric may be used. It will be understood, however, that if desired non-metallic fabric swab elements may be employed. A plurality of flexible abrasive fabric swab elements 17, such as above described, and of suitable area are provided with central openings or perforations 18, and are superimposed one upon the other, preferably in an irregular manner, as illustrated in Figures 10 and 11. When a desired number of said flexible swab elements have been thus assembled together, the same are laid over the outer or free end of the swab head 12, with their perforations 18 aligned with the threaded bore 14 of the latter, whereupon the keeper member 15 is attached to the swab head 12, by passing its threaded shank 16 through the aligned perforations 18, and thereupon screwing the same into the bore 14 of the swab head 12. The flexible swab elements 17 will thus be firmly gripped or clamped intermediate the end of the swab head 12 and the keeper-member 15, so that the free portions of the same may initially overhang and envelope the sides of said swab head 12.

In utilizing the swab, in the simple form thereof above described, the same is inserted in one end of the tubular or cylindrical member, the interior of which is desired to be scoured, (indicated at 19 by dotted lines in Figures 1 and 2), and by means of a

pushing stroke of the handle member 13, is advanced or propelled therethrough. When thus advanced or propelled through the tubular or cylindrical member 19, the flexible swab elements 17 will be compacted by the 70 confining sides of the member 19 around the rigid swab head 12, which thus serves as a base or support against which said flexible swab elements 17 are backed. As thus compacted the flexible swab elements will provide a relatively resilient mass calculated to conform to and frictionally engage the interior wall surfaces of the member 19, while at the same time the myriad of metallic projections, which the metallic fabric comprising said flexible swab elements provides, will exert a highly efficient abrasive scouring action upon the said surfaces of the member 19, which will quickly and easily remove therefrom encrusted or otherwise adhering dirt or soil, whereby the said surfaces are adequately cleaned. As the swab is advanced beyond the end of the member 19, its motion is reversed by means of a pulling stroke of the handle member 13, whereby the 80 flexible swab elements 17 are engaged by the far end of the member 19 and are reversed, (as shown in Figure 2), being thereby folded back to envelop the keeper member 15, and consequently are supported for 85 scouring effect by the latter on the retro-active stroke of the swab device thus initiated.

I have found it desirable in some cases to cover the swab head with an abrasive covering. To this end I provide the swab head 12 with an enveloping jacket or cover 20 made of a metallic abrasive fabric, which may be in kind similar to any of the specific forms of fabric utilized for the flexible swab members 17 as above described. This jacket or cover 20 may consist of one or more layers of metallic abrasive fabric disposed to encircle the swab head 12 and secured thereto at each end by any practical form of fastening means, such as the staples 21, (see Figures 5 and 8). The covering thus provided may be further reinforced against creeping or other displacement by metallic stitching, in either or both longitudinal rows 22 and transverse rows 23. This covering or jacket 20 serves to provide several advantages; first, it provides a more or less resilient abrasive surface in connection with the rigid swab head, which permits the latter to be utilized, with the flexible swab elements detached, for the purpose of preliminary cleaning operations in removing or loosening heavy encrustations of dirt or soil from tubular or cylindrical members 19; and, secondly, when employed in combination with the flexible swab elements 17, provides a frictional surface with which the latter elements may engage to prevent undue pulling strains thereon, while at the same time providing an 100 105 110 115 120 125 130

added resilient cushion backing for the flexible swab elements, tending to increase the yieldable pressure of the same against the interior sides of the member 19 when the device is passed therethrough.

Referring now to Figures 7 to 9 inclusive of the drawings, I have shown therein certain modifications of my novel swab device adapted to furnish the same in a fountain type, whereby steam, water or other fluid may be delivered therethrough during and in aid of the scouring and cleansing effects exerted thereby. In this form my novel swab device comprises a rigid substantially cylindrical swab head 12' which is provided with a tubular handle member 13', the passage 24 of which provides a conduit for conveying a suitable fluid to the swab head 12'. In this case the tubular handle member 13' may be extended throughout the length of the swab head 12', and its outer end may be internally threaded to receive the shank 16 of the keeper member 15. The body of the swab head 12' is provided with a plurality of radial discharge ducts 25 which respectively match lateral discharge openings 26 provided in the walls of said tubular handle member 13', as shown more particularly in Figure 8. In this form of swab device I may provide the swab head 12' with the cover or jacket 20, or it may be omitted as desired. The flexible swab elements 17 are provided and separably attached to the free end of the swab head 12' by means of the keeper member 15 in the manner already above described. As will be understood, when making use of this fountain type of swab device, steam, water or other desired form of fluid may be introduced through the passage 24, and thence discharged through the lateral discharge openings 26 and ducts 25, to flow through the interstices of the covering or jacket 20, and through the interstices of the enveloping folds of said flexible swab elements 17, as the latter are passed back and forth through the member 19, thereby adding to the abrasive scouring effects, the cleansing effects of the supplied fluid. As will be evident from an inspection of Figure 9, the keeper member may also be constructed to provide, if desired, fluid discharge passages in communication with fluid delivery conduit 24 of the handle member 13'. In such case I provide a keeper member body 15' having an externally threaded shank 16' axially imbedded therein so as to project from one end thereof. Said shank 16' is provided with a longitudinal passage 27 to communicate with the conduit 24 of the handle member 13'. The body of the keeper member 15' is provided with a plurality of radial discharge ducts 28 which respectively match lateral discharge openings 29 provided in the walls of the tubular shank 16'. By this modified form of keeper member 15 the

steam, water or other desired fluid may be discharged from the keeper member as well as from the swab head.

I am aware that some changes may be made in the arrangements and combinations of the several devices and parts of my novel swab, as well as in the details of the construction thereof, and I therefore reserve the right to such constructions as do not depart from the scope of this invention as set forth in the foregoing specification, and as defined in the appended claims.

I claim:

1. In a device of the kind described, a rigid elongated head member of suitable cross sectional shape having a handle member extending axially from one end thereof, a keeper member of cross sectional shape and diameter corresponding to that of said head member, means for detachably connecting said keeper member in axial alignment with the free end of said rigid member, and a flexible swab means composed of abrasive metallic fabric material detachably mounted intermediate said head member and keeper member and retained in such relation by the latter, the free ends of said flexible swab means being of such length as to be adapted to fold down and about said head member so as to be backed by the same in one operative position but also adapted to be flexed away from said head to fold upwardly and about said keeper member so as to be backed by the latter in another operative position.

2. In a device of the kind described, a rigid swab head, an external fixed jacket of abrasive metallic sheet fabric secured in fixed enveloping relation to said swab head, a handle member extending axially from one end of said swab head, a flexible swab element composed of abrasive metallic sheet fabric, and means connecting said swab element with the free end of said rigid swab head and permitting said swab element to be flexed over and away from said head.

3. In a device of the kind described, a rigid swab head having a handle member extending axially from one end thereof and an internally threaded bore in the opposite free end thereof, an external jacket of abrasive metallic fabric secured in fixed enveloping relation to said swab head, a flexible swab element composed of abrasive metallic fabric arranged at the free end of said swab head adapted to be flexed over and away from the head, and a keeper member having a threaded shank received in said internally threaded bore of said swab head to detachably clamp said swab element intermediate the latter and said keeper member.

4. In a device of the kind described, a rigid swab head having radial lateral passages, an axial tubular handle member on which said swab head is fixed, said handle member having lateral openings in its walls

registering with said radial lateral passages of said swab head, a flexible swab element composed of abrasive metallic fabric, and means connecting said swab element with the free end of said rigid swab head and permitting said swab element to be flexed over and away from said head.

5. In a device of the kind described, a rigid swab head having radial lateral passages, an axial tubular handle member on which said swab head is fixed, said handle member having lateral openings in its walls registering with said radial lateral passages of said swab head, a flexible swab element composed of abrasive metallic fabric, means connecting said swab element with the free end of said rigid swab head and permitting said swab element to be flexed over and away from said head, and an external jacket of abrasive metallic fabric secured in fixed enveloping relation to said swab head.

6. A swab, comprising a rigid elongated

head member of suitable cross sectional shape having a handle member extending axially from one end thereof, a keeper member of cross sectional shape and diameter corresponding to that of said head member, means for detachably connecting said keeper member in axial alignment with the free end of said rigid member, flexible swab elements detachably mounted intermediate said head member and keeper member, the free ends of said flexible swab-elements being of such length as to be adapted to fold down and about said head member so as to be backed by the same in one operative position but also adapted to be flexed away from said head to fold upwardly and about said keeper member so to be backed by the latter in another operative position.

In testimony, that I claim the invention set forth above I have hereunto set my hand this 29th day of October, 1925.

RUSSELL B. KINGMAN.
